PERPETUAL CALENDAR

Alfred S. Neves, Honolulu, Territory of Hawaii

Application July 1, 1948, Serial No. 36,363

3 Claims. (Cl. 40—113)

1

This invention relates to improvements in perpetual calendars which are adapted to indicate the month of the year, the year, the total number of days in the selected month, and a monthly calendar.

A first object of this invention is to provide a second novel disk consisting of a pair of superimposed circular plates each having indicia selectively positioned in unison at a second inspection opening or window for display of the year. The bottom plate includes groups of three numerals indicating the first three numerals of a given year arranged radially thereon adjacent the edge thereof, and the top plate includes circumferentially spaced segmental sight-openings adjacent the edge thereof and pairs of sequential circumferentially spaced numerals indicating the last numeral of a given year adjacent the inner edges of the segmental sight-openings.

A second object of this invention consists in a monthly perpetual calendar consisting of three rotating disks having a peculiar arrangement of figures, which is combined with a card or frame having openings for exposing portions of the disk.

Yet another object of this invention is the provision of a novel perpetual calendar which is capable of use for many years, having a plurality of rotary disks which carry legends visible through openings, one of the disks bearing the numbers of the days of the month arranged in such form that when this disk is rotated it may be set to agree with any month of any year, means being also provided for taking care of leap year.

Yet another object of this invention is to provide a perpetual calendar of such character that the rotary disk bearing the monthly calendar indicia may be readily and easily replaced with the proposed world calendar, should the latter calendar be adopted in place of the present one.

An additional object is the provision of a device of this character which will be simple and inexpensive in manufacture, highly efficient in use, durable in service, and a general improvement in the art.

With the above and other objects and advantages in view, the invention consists in the details of construction to be hereinafter more fully described and claimed and illustrated in the accompanying drawings, in which

Figure 1 is a plan view of the assembled calendar of the instant invention;

Figure 2 is a sectional view taken substantially on the plane of section line 2—2 of Figure 1;

Figure 3 is a plan view of the central rotary disk bearing the monthly calendar indicia;

Figure 4 is a plan view of the bottom plate of the year indicating disk;

Figure 5 is a plan view of the top plate of the year indicating disk; and

Figure 6 is a plan view of the month indicating rotary disk.

Reference will now be made to the drawings. In the accompanying drawings and in the following specification, similar reference characters indicate corresponding elements throughout. Generally indicated at 10 is a support or holder consisting of a top member 12 and a bottom member 14 secured to each other at appropriate places such as at the corners by means of pins 16 or any other suitable attaching means. As a result of the attachment of the top member to the bottom member at certain desired places, a space 18 is provided between the members for rotatably receiving therein a number of disks to be described hereinafter.

The top member 12 is provided substantially at its center and adjacent its bottom edge with a segmental opening, window or cut-out 20. As seen in Figure 1, above the inner edge of this segmental opening 20 the top member 12 carries the spaced letters S, M, T, W, T, F, and S, indicating the names of the day of the week. Substantially adjacent both sides of the segmental opening 20, the top member 12 is provided with a first transverse opening or window 22 above which is printed the word "Month," and a second transverse opening or window 24 above which is printed the word "Year." The top edges of the top and bottom members 12 and 14 are provided with a longitudinal arcuate cut-out 26 constituting an opening for the display of the day group as seen in Figure 1. Substantially adjacent the bottom of the top and bottom members 12 and 14 a pair of arcuate cut-outs 28 and 30 are provided in the side edges of the top and bottom members.

Rotatably positioned in the support adjacent the cut-out 28, as at 32, is a first disk 34 having a serrated edge 36, a portion of which extends through the cut-out 28, upon the face of which is radially arranged the month of the year, as shown in Figure 6. Thus, by rotating the disk 34 at its edge 36, the month of the year may be selectively displayed in the opening 22.

A second disk is provided which consists of a pair of superimposed plates rotatably positioned in the support, as at 38, adjacent the cut-out 28. The bottom plate 40 is provided with a serrated edge 42, a portion of which extends through the cut-out 30 and carries on its face, adjacent the

serrated edge, groups of three numerals indicating the first three numerals of a given year arranged radially thereon as shown in Figure 4. The top plate 44 is also provided with a serrated edge 46, a portion of which also extends through the cut-out 30. This top plate includes circumferentially spaced segmental side openings 48 adjacent the serrated edge and carries pairs of sequential, circumferentially spaced numerals indicating the last number of a given year adjacent the inner edges of the segmental side openings 48, as shown in Figure 5. Thus, by the proper rotation of the bottom and top plates, the first three numerals and the last numeral of a given year may be selectively positioned for display in the opening 24.

Rotatably positioned in the support and substantially at its center, as at 50, is a central rotary disk 52 which is also provided with a serrated edge 54. This disk is provided with four sets of figures arranged in concentric lines 56 and radial columns 58. It will be observed that each set of figures is contained in a sector 60 which consists essentially of thirteen radial columns and five concentric zones. These thirteen radial columns, in effect, consist of a pair of six columns 62 and 64 separated by an intermediate radial column 66. The figures commence in the innermost portion 68 of the intermediate radial column 66 and are arranged to run consecutively in each of the six columns 62 and 64, the intermediate column 66 having figures in common with the consecutive arrangement provided in the columns 62 and 64. The arrangement of numerals is such that the numerals commence with numeral 1 in the portion or box 68 and proceed in advancing order counter-clockwise in the innermost concentric or first zone. In the next or second concentric zone, the numerals commence with numeral 2 in the extreme left-hand box and proceed in advancing order to the right across all thirteen radial columns. In the next or third concentric zone, the numerals commence with numeral 9 in the extreme left-hand box and proceed in advancing order to the right across all thirteen columns. In the next or fourth concentric zone, the numerals commence with numeral 16 in the extreme left-hand box and proceed in advancing order to the right across all thirteen columns. And in the next or fifth concentric zone, the numerals commence with numeral 23 and proceed in advancing order. It will be understood that the window or cut-out 20 subtends seven radial columns.

Also arranged on the disk 52 above each of the zones 62 and 64 and adjacent the serrated edge 54 are pairs of circumferentially spaced day group indicia. As will be seen in Figure 3, these day groups run from 28 through 31. The serrated edge 54, as will be seen in Figure 1, extends through the cut-out 26.

In practical operation of the device, it will readily be seen that the operator need only position the proper day group in the cut-out 26 and rotate the disk 52 in such manner that the first day of the given month corresponds with the name of the day upon which it falls. The procedure is repeated each month to keep the calendar up to date.

Having described the invention, what is claimed as new is:

1. A perpetual calendar indicator comprising a support having a plurality of inspection openings therein and having a chamber rotatably housing a plurality of indicia-bearing disks each

of which is selectively positionable to exhibit its indicia at one of said openings, one of said disks having indicia designating the month of the year, a second disk consisting of a pair of superimposed circular plates each having indicia selectively positioned in unison at a second inspection opening for display of the year, and a third disk having groups of indicia thereon for display at third and fourth openings, the indicia displayed at the third opening consisting of day groups, the indicia displayed at the fourth opening consisting of a monthly calendar, said groups of indicia being correlated to properly display a monthly calendar of the chosen day group of the other group of indicia, said third disk including four sets of figures arranged in concentric lines and radial columns and a pair of day groups associated with each of said sets arranged circumferentially adjacent the edge of said disk, said first-mentioned disk including indicia arranged radially thereon, the bottom of said circular plates including groups of three numerals indicating the first three numerals of a given year arranged radially thereon adjacent the edge thereof and said top plate including circumferentially spaced segmental sight-openings adjacent the edge thereof and pairs of sequential circumferentially spaced numerals indicating the last numeral of a given year carried by said top plate adjacent the inner edges of said segmental sight-openings.

2. A perpetual calendar indicator comprising, a support having a plurality of inspection openings therein and having a chamber rotatably housing a plurality of indicia-bearing disks each of which is selectively positionable to exhibit its indicia at one of said openings, one of said disks having indicia designating the months of the year, a second disk consisting of a pair of superimposed circular plates each having indicia selectively positioned in unison at a second inspection opening for display of the year, and a third disk having day group indicia arranged circumferentially adjacent the edges thereof for display at a third opening, said third disk including four groups of thirteen radial columns and five concentric zones, the numerals in each group being arranged as follows: commencing with numeral 1 in the seventh radial column and in the innermost concentric zone, the numerals proceed in advancing order counter-clockwise in said concentric zone; commencing with the numeral 2 in the extreme left radial column and in the second concentric zone, the numerals proceed in advancing order counter-clockwise across all of the thirteen radial columns; commencing with the numeral 9 in the extreme left radial column and in the third concentric zone, the numerals proceed in advancing order counter-clockwise across all of the thirteen radial columns; commencing with the numeral 16 in the extreme left radial column and in the fourth concentric zone, the numerals proceed in advancing order counter-clockwise across all of the thirteen radial columns; and commencing with the numeral 23 in the extreme left radial column and in the fifth concentric zone, the numerals proceed in advancing order counter-clockwise, said support having a fourth opening of such size as to subtend seven radial columns and five concentric zones.

3. The combination of claim 1 wherein said third disk includes four groups of thirteen radial columns and five concentric zones, the numerals in each group being arranged as follows: commencing with numeral 1 in the seventh radial

column and in the innermost concentric zone, the numerals proceed in advancing order counter-clockwise in said concentric zone; commencing with the numeral 2 in the extreme left radial column and in the second concentric zone, the numerals proceed in advancing order counter-clockwise across all of the thirteen radial columns; commencing with the numeral 9 in the extreme left radial column and in the third concentric zone, the numerals proceed in advancing order counter-clockwise across all of the thirteen radial columns; commencing with the numeral 16 in the extreme left radial column and in the fourth concentric zone, the numerals proceed in advancing order counter-clockwise across all of the thirteen radial columns; and commencing with the numeral 23 in the extreme left radial column and in the fifth concentric zone, the

numerals proceed in advancing order counter-clockwise, the fourth opening being of such size as to subtend seven radial columns and five concentric zones.
